UNITED STATES PATENT OFFICE.

FRANK J. MATHIAS, OF FREMONT, OHIO.

SPARK-PLUG.

1,253,072.

Specification of Letters Patent.

Patented Jan. 8, 1918.

Application filed February 28, 1917. Serial No. 151,548.

To all whom it may concern:

Be it known that I, FRANK J. MATHIAS, a citizen of the United States, residing at Fremont, in the county of Sandusky and State of Ohio, have invented certain new and useful Improvements in Spark-Plugs, of which the following is a specification.

This invention relates to spark plugs.

One of the main objects of the invention 10 is to provide a spark plug for an internal combustion engine in which the spark points or terminal members may be adjusted toward or away from each other so as to vary the spark gap to suit circumstances. A further 15 object is to provide a spark plug of simple construction which may be produced at very small cost having a removable cover by means of which access to the interior of the plug may be had without removing the 20 plug from the engine cylinder. A further object is to provide a spark plug having a removable cover provided with a pet-cock by means of which communication between the 25 interior of the plug and the atmosphere may be established for cleaning the terminal members in the event of these members becoming fouled. A still further object is to provide a plug so constructed that carbon sticks may be used as terminal members 30 thus permitting these members to be quickly and easily renewed at very small cost.

In the drawings:—

Figure 1 is a side view of a spark plug constructed in accordance with my invention,

Fig. 2 is a section taken on line 2—2 of Fig. 3,

Fig. 3 is a central vertical section through the plug.

The plug made of hardened steel, iron, or other suitable material, is provided with a cylindrical hollow body 1 and reduced neck 2 integral therewith which is exteriorly threaded as at 2^a so as to permit the 40 plug to be readily secured through the wall of an engine cylinder in the usual manner. The upper portion of body 1 is exteriorly threaded to receive a cover or closure member 3 threaded thereon which is provided 45 with an integral hexagonal flange 4 so as to permit the cover to be secured tightly onto the body. Cover 3 is of approximately 50 hemispherical shape and is provided, at its center, with a threaded bore into which is threaded the stem of a pet-cock 5.

The body 1 is provided with a flattened

portion 6. An opening is provided through this flat portion and receives an insulating thimble 7 of mica or other suitable insulating material, this thimble being provided at 50 each end with an integral annular flange 7^a which projects beyond the periphery of the opening. Thimble 7 is provided with a central bore which snugly receives a terminal member supporting rod 8. Rod 8 is provided with the threaded portions 8^a and 8^b adjacent each end of thimble 7. A nut 9 is threaded on the rod adjacent the outer end of the thimble, a similar nut 10 being threaded on the rod adjacent the inner end 70 of the thimble. These two nuts coact to compress the insulating thimble 7 so as to force the same into tight engagement with the body 1 of the plug about the opening through the flattened portion 6 thus forming 75 a fluid tight closure therewith. The nuts also act to secure the rod 8 in axial adjustment through the thimble.

Rod 8 is provided, adjacent its inner end, with a diametrical bore adapted to receive 80 a terminal member 11, this member being a pencil or stick of carbon. Terminal member 11 may be adjusted through the rod 8 by means of a set screw 12 threaded into the rod and engaging this member. A holding 85 block 13 of any suitable electrical conducting material is secured to the base of body 1 adjacent neck 2. This block is provided with a vertical bore which receives the lower end of a carbon stick 14 corresponding to 90 stick 11. A set screw 15 serves to secure the terminal member 14 in position.

This plug is especially adapted for use with high tension ignition systems, the terminal member 14 being electrically connected 95 to one side of this system by means of the engine and the base frame in the usual manner. The terminal member 11 may be connected to the other side of the ignition system by means of a connecting nut 16 threaded on the outer end of rod 8 which cooperates with an annular shoulder 17 to secure the end of the conductor or wire to the rod. In using this plug the current in passing from one terminal member to the 100 other will cause a spark igniting the charge of explosive mixture in the cylinder in the usual manner. By adjusting the rod 8 through thimble 7 the spark gap may be varied as desired. Also, by adjusting the 110 terminal member 11 through rod 8 all wear of the two terminal members may be ac-

commodated, and the vertical height or width of the spark gap may be varied so as to vary the intensity of the spark.

In the event of the terminal members 11 and 14 becoming fouled, the pet cock 5 may be opened, and the engine operated so as to clean these terminal members in the usual manner. The cover 3 may be quickly and easily removed from the body 1 when necessary so as to permit access to the interior of the plug for adjusting or renewing the terminal members, or for adjusting the rod 8 axially so as to vary the width of the spark gap, and may be as quickly and easily replaced when the desired adjustment has been made.

A spark plug constructed in accordance with my invention may be produced at very small cost, and permits quick and easy adjustment of the terminal members, it being possible to obtain access to the interior of the plug without the necessity of removing it from the engine cylinder. In addition, I am enabled to use terminal members made of carbon which may be produced at very small cost, one of these members being adjustable so as to accommodate wear of the terminals due to arcing between the same.

What I claim is:—

30 1. In spark plugs, a hollow body, a terminal member carried by said body and electrically connected thereto, a terminal member supporting rod secured through the wall of said body and electrically insulated therefrom, and a terminal member adjustably mounted in said rod adjacent the inner end thereof and movable toward and away from the terminal member carried by the body of said plug.

2. In spark plugs, a hollow body, an upwardly extending terminal member carried by said body and electrically connected thereto, a terminal member supporting rod secured through the wall of said body and electrically insulated therefrom, and a terminal member carried by said rod and extending in parallel spaced relation to the terminal member carried by the body of the casing, the terminal member carried by said rod being axially adjustable whereby the effective height of the spark gap between the two said terminals may be varied.

3. In spark plugs, a hollow cylindrical body, an insulating thimble mounted through the wall of said body, a terminal member supporting rod mounted through said thimble, adjusting nuts threaded on said rod adjacent each end of the thimble, means for securing a terminal member to said rod at the inner end thereof, a terminal member carried by said body, and a closure member removably secured on said body.

4. In spark plugs, a hollow body, a terminal member carried by said body and electrically connected thereto, a terminal member supporting rod adjustably secured through the wall of said body and electrically insulated from the same, a terminal member adjustably secured through said rod adjacent the inner end thereof, and a closure member removably secured on said body.

In testimony whereof I affix my signature in presence of two witnesses.

FRANK J. MATHIAS.
